UNITED STATES PATENT OFFICE.

JOSEPH FRITSCHI AND WILLIAM P. HUGHES, OF HONOLULU, TERRITORY OF HAWAII.

CANE-LOADING APPARATUS.

Application filed September 14, 1921. Serial No. 500,491.

To all whom it may concern:

Be it known that we, JOSEPH FRITSCHI and WILLIAM P. HUGHES, citizens of the United States, residing at Honolulu, Territory of Hawaii, have invented certain new and useful Improvements in Cane-Loading Apparatus; and we do hereby declare the following to be a full, clear, and exact description of the invention, such as will enable others skilled in the art to which it appertains to make and use the same.

This invention relates to conveyors and particularly to an apparatus of this character primarily intended for use in the loading of sugar cane into cars directly from the field, although of course it is to be understood that the same is equally well adapted for loading other material of a similar nature.

The use of conveyors of different designs for the loading of sugar cane and the like into cars in the field is well known and not broadly new, but in these previous types commonly used, the conveyors have been mounted on truck wheels, caterpillar tractors or automobile chassis, which conveyed them to and from their different loading positions.

The principal object of the present invention is to eliminate these various expensive means of transportation, and resides in a construction whereby the bulk of the weight of the conveying apparatus, while in operation, rests on track sections carried by the car that is being loaded, the outer or lower end thereof being preferably provided with a light framework or a steel plate resting on the ground, it being desirable to have said outer end as low as possible so that the cane will not have to be elevated while being piled on the conveyor. It is also contemplated to provide a horizontal conveyor section extending from the lower end, which will allow more room for the gang of loaders to throw the cane on the conveyor without interfering with each other.

Another object of the invention is to construct and mount the rail sections carried by each car so that they can be connected up to the rail sections of the adjoining car, thus permitting the conveying apparatus to

be moved along from the car that has been loaded to the next car to be loaded, means being provided to elevate and support the outer end of the conveyor during this operation.

Briefly stated, the apparatus comprises a pair of oppositely disposed inclined side frame members of structural steel or tubes mounted each side of a loaded car, each consisting of a series of parallel tubes or rods having their upper ends connected by a transverse rod or tube, and their outer or lower ends secured to a transverse steel plate or beam adapted to rest on the ground or upon supporting legs secured thereto, as preferred. The upper end of each inclined frame member is supported upon vertically disposed standards, the lower ends of each being secured to substantially horizontally disposed tubes extending and secured to the lower outer ends of the outside parallel tubes or rods of the inclined frame. The extreme lower ends of the vertical standards are provided with flanged wheels or rollers whereby the inner end of the inclined frame is adapted to be supported upon tracks or the like disposed along the sides of the car with which the apparatus is to be used during the loading operation.

Moving over the face of each of these inclined members is a conveying means comprising a series of endless wire cables or chains running around sheaves or sprockets, as preferred, properly disposed along the upper and lower ends of said inclined members, means being provided for operating or rotating the sheaves.

Extending upwardly from each vertical standard, supporting the elevated end of the conveyor, is an upright projecting above said elevated end of the conveyor, the oppositely disposed uprights of both inclined conveyor being connected together to maintain said conveyors in proper relative positions during the operation thereof. The extreme upper ends of the uprights are in addition provided with roller sheaves by means of which, together with a cooperating cable and windlass, said uprights may be drawn toward each other, when desired to raise the lower ends of the conveyors from

the ground, prior to the moving thereof, on their supporting tracks, to their new loading position.

The preferred embodiment of the invention is illustrated in the accompanying drawings, in which—

Fig. 1 is a view in elevation showing the oppositely disposed conveyors in operative position.

Fig. 2 is a side elevation on a larger scale, part being broken away for the purpose of convenience in illustration, and

Fig. 3 illustrates an alternative construction involving the use of an additional horizontal conveyor adapted to be associated with each inclined conveyor.

Referring to the drawings in detail, the apparatus comprises a pair of oppositely disposed inclined frame members, which consist of a series of parallel inclined tubes or rods 1, having their upper ends connected by a transverse rod or tube 2, and their lower ends secured to a transversely disposed plate or beam 3, which plate during the loading operation is adapted to rest upon the ground. If desired, instead of the plate 3 resting directly upon the ground, the said plate may be supplied with a light framework comprising legs 4, as clearly shown in the drawings.

The upper end of the inclined member just described is supported upon vertically disposed standards 5, the lower ends of said standards being connected to the lower ends of the outside inclined rods 1 of the frame member by a substantially horizontal strut or brace 6, and, if desired, an intermediate substantially vertical brace 7 may be applied.

The extreme lower end of each vertically disposed standard 5 is supplied with a flanged wheel or roller 8 engaging a track 9 secured to each side of a loading car 10, whereby the inner end of the inclined frame member is movably supported.

Moving over the face of each of the inclined frame members is a conveying means comprising a series of endless wire cables or chains 11 supported upon sheaves or sprockets 12 and 13. The sheaves 12, mounted at the elevated end of the conveyor frame, are supported upon a shaft 14 properly journalled in bearings 15 carried by extensions 16 of the inclined tubes or rods 1. The lower sheaves 13 are mounted upon a shaft 17 secured in proper position by yokes or brackets 18 attached to the plate or cross beam 3. The sheaves 13 are freely rotatable upon their shaft 17 or said sheaves may be secured to said shaft, the shaft itself in this event being freely rotatable in its supporting brackets 18. The sheaves 12 are keyed to their supporting shaft 14, one end of said shaft being supplied with a gear 19 meshing with a worm 20 mounted upon a shaft 21 op-

erated by a motor 22, whereby the shaft 14 will be rotated, which operation will in turn rotate its supported sheaves 12, carrying with them the conveyor cables 11, the sheaves 13 merely idlying upon their supporting shaft 17 in an obvious manner.

In order to provide a gripping action between the conveyor cables and cane during the operation of the apparatus, and to prevent said cane from slipping, the conveyor cables 11 are provided with knots or projections 23 arranged at certain intervals throughout the length of each conveyor cable. In this connection it is to be understood that light detachable chains running on sprockets can be used instead of wire rope, certain links of said chain having attached thereto projections to prevent slipping, in a manner similar to that just described.

It is to be noted also that in place of the motor 22, represented as an electric motor, a small gasoline engine may be employed, preferably with a belt drive to the shaft 14.

Extending upwardly from each vertical standard 5 is an upright 24 projecting above the elevated end of the conveyor, and the upper ends of the uprights of each conveyor section are connected by stay wires or the like 25. The upper ends of the oppositely disposed uprights of the two conveyor sections are likewise connected together by stay wires 26, whereby the lower position of the outer lower ends of said conveyor sections may be properly regulated.

The extreme upper ends of the uprights 24 are supplied with sheaves 27 adapted to co-operate with cables 28 running around winding drums or windlasses 29, whereby upon the operation of said winding drums the uprights 24 may be drawn together when it is desired to elevate the lower outer ends of the conveyor sections during the moving of said conveyor sections from one loading position to another.

To permit the conveyors to be moved along the tracks 9 from a loaded car to the next car to be loaded, it is necessary that said tracks be continuous, necessitating a means of joining the abutting ends of the track sections carried by each individual car. This has been accomplished by constructing the track sections 9 of pipe and securing their ends together by telescoping joint involving the use of a pin or the like 30, as clearly shown in Fig. 2.

In the modification illustrated in Fig. 3, a relatively short horizontally disposed conveyor section, connected to the lower end of the inclined main conveyor, is shown. If this supplemental conveyor section is used, additional sheaves or sprockets are mounted on the shaft 17 between the sheaves or sprockets 13 for supporting one end of each

of the supplemental conveyor cables or chains 11', the opposite ends being supported upon sheaves or sprockets 13' freely rotatable upon a shaft 17'. This shaft 17' may be connected to the lower end of the main conveyor by a frame construction of any approved type and supported from the ground by legs or the like 4', similar to the manner of supporting the lower ends of the main conveyors. When this supplemental horizontal conveyor is used the sheaves or sprockets 13 are keyed to the shaft 17, whereby said shaft will be rotated so that by securing to said shaft the sheaves or sprockets supporting the inner ends of the supplemental conveyor cables, said conveyor will be operated by the main conveyor. The frame securing the supplemental conveyor to the main conveyor may be hinged to the lower end of said main conveyor, so that the same may be thrown over on top of the main conveyor prior to the change of the position thereof, or said supplemental conveyor frame may be rigidly connected whereby the same will be merely raised from the ground along with the main conveyor during the elevation thereof, when it is desired to change the position of the main conveyor.

From the foregoing description, the operation of the apparatus, it is believed, will be perfectly obvious. When a car is loaded and it is desired to move the conveyors, the lower ends thereof are elevated upon the operation of the winding drums 29 cooperating with their respective cables 28, whereby the upper ends of the uprights 24 will be drawn together, the conveyor frames swinging upon their supporting rails as a center. The outer ends are thereby lifted from the ground and the whole weight thereof taken on the portable rails carried by the loading cars. The conveyors are then pushed by hand, or pulled by any preferred mechanical means, to a new position adjacent the empty car to be loaded. If preferred, the flanged rollers 8 supporting the elevated ends of the conveyors may be provided with roller or ball bearings so that they will move with the least possible friction.

With the above construction a whole train of cars may be quickly and successively loaded in a very simple and effective manner, requiring only the minimum amount of manual labor.

It is to be understood that instead of supporting the inner ends of the conveyor upon trackways carried by the cars, the same may conveniently be movably mounted upon tracks, or trackways adjacent the train of cars, and, if necessary, the vertically disposed standards, 5, may be lengthened to accommodate this arrangement.

What we claim is:

1. A loading apparatus, comprising oppositely inclined conveyors, means for con-

necting the adjacent ends thereof in spaced relation, means for supporting the elevated ends of each conveyor for conjoint lateral movement of said conveyors, and means for raising the lower ends of the conveyors. 70

2. A loading apparatus, comprising oppositely inclined conveyors, means for connecting the adjacent ends thereof in spaced relation, wheels on the elevated ends of the conveyors, tracks engaged by the wheels to 75 permit conjoint lateral movement of said conveyors, and means for raising the lower ends of said conveyors.

3. A loading apparatus, comprising oppositely inclined conveyors, means for connecting the adjacent ends thereof in spaced relation, wheels on the elevated ends of the conveyors, tracks disposed laterally of the vehicle to be loaded, said tracks engaging the wheels to permit conjoint lateral movement of said conveyors with respect to the loading vehicle, and means for raising the lower ends of said conveyors. 80 85

4. In a loading apparatus, the combination with a loading car, of oppositely disposed inclined conveyors adapted to be positioned each side of said car, means carried by said car for movably supporting the elevated ends of said conveyors, means for supporting the lower outer ends of said conveyors when in operative position, means for raising said lower outer ends, and an independent driving unit carried by each conveyor. 90 95

5. In a loading apparatus, the combination with a loading car, of oppositely disposed inclined conveyors adapted to be positioned each side of said car, wheels carried by the elevated end of each conveyor, tracks secured along each side of said car upon 100 which said wheels are movably supported, means for supporting the lower outer ends of said conveyors, uprights secured to and extending above the elevated ends of each conveyor, winding cables connecting the uprights of the oppositely disposed conveyors for raising the lower ends thereof, and independent motors for operating each conveyor. 105 110

6. In a loading apparatus, the combination with a train of loading cars, of oppositely disposed inclined conveyors adapted to be positioned to each side of said train, track wheels carried by the elevated ends of each conveyor, track sections secured along each side of each car upon which said wheels are movably supported, means for connecting the ends of the track sections of the adjacent cars of the train to form a continuous track, means for supporting the lower outer ends of said conveyors when in operative position, a horizontal conveyor section connected to the lower outer ends of each inclined conveyor, independent motors for operating each conveyor, and means connecting the upper ends of the oppositely dis- 115 120 125 130

posed conveyors for raising the lower ends thereof to permit the changing of the loading position of said conveyors.

7. A loading apparatus, comprising an inclined conveyor frame member consisting of a series of inclined rods, and an upper and a lower end connecting rod and plate, respectively, vertically disposed standards supporting the elevated end of said conveyor frame, wheels carried by the lower ends of said vertical standards for movably supporting the elevated end of said frame from a loading car or the like, means for supporting the lower end of said conveyor frame upon the ground, shafts carried by the upper and lower ends of said conveyor frame, a series of endless conveying elements supported by said shafts, a motor mounted upon said frame for operating the conveying elements, vertical uprights secured to and extending above the elevated end of said conveyor frame, and a winding cable connected to said uprights for raising the lower end of the conveyor frame to permit the changing of the loading position thereof.

8. In a loading apparatus, the combination with a train of loading cars, of a pair of oppositely disposed conveyor frame members, each comprising a series of inclined rods and an upper and a lower end connecting rod and plate, respectively, vertically disposed standards supporting the elevated end of each conveyor frame, track wheels carried by the lower ends of said vertical standards, track sections secured along each side of each car upon which said wheels are movably supported, means for connecting the ends of the track sections of the adjacent cars of the train to form a continuous track, means for supporting the lower outer ends of said conveyor frames when in operative position, shafts carried by the upper

and lower ends of each of said frames, a series of endless conveying elements supported by said shafts, a separate motor for operating the conveying elements of each conveyor frame, vertical uprights secured to and extending above the elevated end of each of said frames, and winding cables connecting the oppositely disposed uprights of the conveyor frames for raising the lower ends thereof to permit the changing of the loading position of said conveyors.

9. In a loading apparatus, the combination with a loading car, of oppositely disposed inclined portable conveyors adapted to be positioned each side of said car, means positioned at the sides of said car for movably supporting the elevated ends of said conveyor, means for supporting the lower outer ends of said conveyors when in operative position, means for raising said lower outer ends, and an independent driving unit carried by each conveyor.

10. In a loading apparatus, the combination with a train of loading cars, of oppositely disposed inclined conveyors adapted to be positioned at each side of said train, track wheels carried by the elevated ends of each conveyor, track sections positioned at each side of said train upon which said wheels are movably supported, means for supporting the lower outer ends of said conveyors when in operative position, independent motors for operating each conveyor and means connecting the upper ends of the oppositely disposed conveyors for raising the lower ends thereof to permit changing of the loading position of said conveyors.

In testimony whereof we affix our signatures.

JOSEPH FRITSCHI,
WILLIAM P. HUGHES.
